SPRAY CABINET FOR DISINFECTING BEVERAGE CASES

Eugene P. Reagan, 3848 Blaisdell Ave., Minneapolis,
Minn.; Eileen Reagan, special administratrix of said
Eugene P. Reagan, deceased

Filed Aug. 26, 1963, Ser. No. 76,351

Term of patent 14 years

(Cl. D9—2)

FIG. 1

FIG. 3

FIG. 1 is a front perspective view taken from one end of the spray cabinet for disinfecting beverage cases embodying my new design; and

FIG. 2 is a rear perspective view taken from the end shown in FIG. 1.

FIG. 3 is a front perspective of the cabinet.

I claim:

The ornamental design for a spray cabinet for disinfecting beverage cases, substantially as shown.
